EDWIN W. HAMMER, OF EAST ORANGE, NEW JERSEY, ASSIGNOR TO CLINE ELECTRIC
MANUFACTURING COMPANY, OF CHICAGO, ILLINOIS, A CORPORATION OF ILLINOIS

MEANS FOR MAKING HIGH-SPEED PASTERS

Application filed March 11, 1925. Serial No. 14,637.

In the printing of newspapers there are certain factors which are unique in that the printing of a newspaper edition is postponed to the very last practicable moment, in order to include the latest news, but when the printing of the edition begins, the aim is to complete the running off of the edition as soon as possible in order that the papers may be distributed or sold without delay. In consequence of this demand, there has been developed apparatus which is in daily use in many newspaper printing plants whereby a plurality of rolls of paper are made immediately available at the press so that as one roll of paper becomes depleted, a fresh roll may be quickly brought into position to take its place. This is effected through the use of a magazine reel or roll stand having a rotatable member with extending arms adapted to carry a plurality of rolls. The common form of this apparatus includes a press-driven traveling belt arrangement so placed as to maintain the surface of the traveling belt in contact with the active roll of paper. Such belt may be arranged to drive the roll or retard it if desired, and is of assistance in effecting what is known as a flying paster.

The flying paster is another out-growth of the demand for time-saving in the newspaper plant and is the joining of the web from a fresh roll to the expiring web of a depleted roll without actually stopping the press. Before the flying paster was evolved it was necessary to stop the press each time a new roll was to be introduced and this involved a delay of several minutes. As the usual roll expires in about twenty minutes run, this means a replacing of each roll three times an hour with a loss of nine minutes per hour for each roll running to press. In a press using four rolls it will be seen that more than fifty percent of the time was taken up in changing rolls, because it practically never happens that two rolls can be changed at precisely the same time. The flying paster cut down the time of making the change very materially, because the combination of magazine roll and press slowing (instead of press stoppage) has cut down the usual time of making a change to a minute and a half, or a little less. It is

thus seen that a press capable of turning out thirty-thousand copies per hour if run continuously never turns out thirty-thousand an hour because so much time is taken up in slowing the press, making the flying paster and re-accelerating the press once more. In order to make the flying paster it is usual to cut the press speed down to one-quarter or less its full speed rate. It is thus evident that although the flying paster was a distinct help, it is a flying paster only in name as there has never been in practical operation a newspaper press in which a fresh roll can be attached to an expiring web at high speed.

It is the object of the present invention to provide an apparatus with which a paster may be made at high speed. The preferred form of apparatus embodying this invention is shown in the accompanying drawing in which a magazine roll stand is illustrated, embodying pedestals 1 adapted to support a shaft 2 upon which are mounted spiders with arms 3 adapted to carry rolls of web-paper 4, 5 and 6. On the roll stand is an electric motor 7 for adjusting the spiders so as to place the active roll of paper in proper position and to bring a fresh roll into proper position to resume the supplying of web-paper to the press. The motor 7 drives the large gear wheel 7^a secured to the spiders, through proper gearing. Another electric motor 8 is utilized to shift the rolls of paper laterally so as to adjust the margin.

Pressing against the active roll 4 is a traveling belt 9 moving in the same direction as the web 4^a going to press, such traveling belt 9 being carried by two pulleys 13 and 14 mounted upon a frame 12 pivoted at its upper end to a press-driven shaft 10 supported in hangers 11. This is the conventional apparatus used for many years. To this apparatus I have added a second belt 15 running over pulleys 18 and 19 supported in a frame 17 pivoted at its upper end upon a shaft 16 held in hangers 22. The shaft 16 is also press-driven and may have an independent connection to the press drive or it may be driven from the shaft 10 by a sprocket chain 20 or may receive its driving force in any other convenient manner, provided

the result is a driving of the shaft 16 at such a rate as to give a speed to the belt 15 equal to that of the web 4^a going to press from the active roll 4 over the roller 21. The frame 17 is preferably arranged at its upper end so as to permit its being moved laterally along the shaft 16 which is provided with a continuous feather or key to permit such movement while maintaining driving connection 10 with the pulley 18. This adjustable feature permits the belt 15 to rest at any convenient point upon the roll 5 which at times is of full length or of fractional length, depending upon the number of pages in the edition being printed. A chain or cord 17^a is 15 preferably employed to hold the frame 17 away from the roll except when it is desired to utilize the belt 15 for the rotation of the roll 5.

20 It will be understood that in the operation of this apparatus the end of the new web on roll 5 is trimmed and has applied thereto a suitable adhesive, the flap of the web being held down against the surface of the roll 5 by grease or some other light adhesive. When the high speed paster is to be made, at a time when the roll 4 is nearly exhausted, the belt 15 is brought into contact with the roll 5 at a convenient point, where adhesive has 25 not been applied, and the roll 5 is thereupon caused to rotate and come up to the speed of the belt 15, which is the speed of the web 4^a. When this condition has been reached, the reel is rotated by the motor 7 and the 30 roll 5 brought into contact with the web 4^a. If the movement of the reel is carried forward sufficiently, the pressure of the roll 5 will force the web 4^a into contact with the belt 9 and this may assist in effecting adhesion of 35 the gummed portion of the web on roll 5 to the outgoing and nearly expired web 4^a. Adhesion is readily and safely made because the new web and the old web are both traveling at the same speed. When adhesion has taken 40 place the old web is broken back of the joint and the reel is turned still further to bring the new roll into the most favorable position for supplying its web to the press. The arm 3 carrying the old roll 4 has by this 45 action been swung around to the left of the pedestal 1, where it may be readily removed and a fresh roll substituted for it to prepare 50 for a later use.

I claim as my invention the following:

- 55 1. In an apparatus of the character described the combination of a rotatable magazine reel adapted to carry a plurality of rolls of paper, a normally inactive but press-driven belt adapted to be brought in contact with a fresh roll of paper to rotate the same and bring it to web-speed preliminary to making a paster, and means for rotating the reel to effect contact of the fresh roll with the traveling web from the expiring roll.
- 60 2. In an apparatus of the character described the combination of a rotatable maga-

zine reel adapted to carry a plurality of reels of paper, rolls of paper mounted thereon, a normally inactive but press-driven belt adapted to be brought in contact with a fresh roll of paper having adhesive applied to the outer end thereof to rotate the same and bring it to web-speed preliminary to making a paster, and means for rotating the reel to effect contact of the fresh roll with the traveling web from the expiring roll.

3. In an apparatus of the character described the combination of a rotatable magazine reel adapted to carry a plurality of rolls of paper, a traveling belt adapted to rest against the active roll and control the rotation thereof, a normally inactive belt, also press-driven, adapted to be brought in contact with a fresh roll of paper to rotate the same and bring it to web-speed preliminary to making a paster, and means for rotating the reel to effect contact of the fresh roll with the traveling web to press the latter against the first mentioned belt to assist in effecting adhesion of the new web to the old.

4. In an apparatus of the character described the combination of a rotatable magazine reel adapted to carry a plurality of rolls of paper, rolls of paper mounted thereon, a press-driven belt adapted to rest against the active roll and control the rotation thereof, a normally inactive but press-driven belt adapted to be brought in contact with a fresh roll of paper having adhesive applied to the outer end thereof to rotate the same and bring it to web-speed, and means for rotating the reel to effect contact of the fresh roll with the traveling web and press the latter against the first mentioned belt to assist in securing adhesion of the web of the fresh roll to the expiring web.

5. In an apparatus of the character described the combination of a rotatable magazine reel adapted to carry a plurality of rolls of paper, rolls of paper mounted thereon, a normally inactive but press-driven belt, means by which said belt may be brought in contact with a fresh roll of paper having adhesive applied to the outer end thereof to rotate the same and bring it to web-speed, and means for rotating the reel to produce a paster of the new web to the traveling web from the expiring roll.

6. In an apparatus of the character described the combination of a rotatable magazine reel adapted to carry a plurality of rolls of paper, rolls of paper mounted thereon, a press-driven belt adapted to rest against the active roll and control the rotation thereof, a normally inactive but press driven means adapted to be brought in contact with a fresh roll of paper having adhesive applied to the outer end thereof to rotate the same and bring it to web-speed, and means for rotating the reel to effect contact of the fresh roll with the traveling web

and press the same against the press driven belt to aid in making a paster of the new web upon the expiring web.

7. In an apparatus of the character described the combination of a rotatable magazine reel adapted to carry a plurality of rolls of paper, controlling means adapted to press against the active roll and control the rotation thereof, a normally inactive driving means adapted to be brought in contact with a fresh roll of paper to rotate the same and bring it to web-speed preliminary to making a paster, and means for rotating the reel to effect a contact of the fresh roll with the traveling web, to press the latter against the controlling means to assist in effecting adhesion of the new web to the old.
